UNITED STATES PATENT OFFICE.

ARA D. CROCKER, OF SHEBOYGAN, WISCONSIN, ASSIGNOR TO THE CROCKER CHAIR COMPANY, OF SAME PLACE.

DESIGN FOR A CHAIR.

SPECIFICATION forming part of Design No. 29,849, dated December 20, 1898.

Application filed November 25, 1898. Serial No. 697,458. Term of patent 7 years.

To all whom it may concern:

Be it known that I, ARA D. CROCKER, a citizen of the United States, residing at Sheboygan, in the county of Sheboygan and State 5 of Wisconsin, have invented and produced a new and original Design for Chairs; and I do hereby declare the following to be a full, clear, and exact description of the same, reference being had to the accompanying drawing, forming a part thereof.

The said drawing is a perspective view of a chair embodying my new design.

My design relates to the new and original shape or configuration of the article.

15 The leading or essential feature consists in the unitary design for a chair made the subject of illustration, comprising the inclined back A, with rounded upper corners B formed on the lines of arcs of circles, united 20 at the center of the top of the back by a triangular upward projection C, curved rear legs D, the upper parts of which are wholly back of the said back A, front legs E, curved at both front and rear, said legs E being 25 formed with short backwardly-extending curved portions b at their upper ends, abrupt forwardly-curved portions c just below their tops b and extending down to about the line of the seat F and merging into rearwardly- 30 curved portions d below the seat, and forwardly-curved lower portions e, terminating

in feet f, having nearly straight abrupt front surfaces, the front leg E and rear leg D on each side of the chair being connected by a brace G near the lower ends of said legs and 35 by a concaved arm H, resting on the top of the front leg E and on a rounded-edged piece I, resting on the top of the rear leg D, there being a flat baluster K between the brace G and arm H on each side.

40

Minor features of said design comprise the shape of said baluster, which has narrow upper and lower ends g h, with concave front and rear edges and a wide convex-edged and generally oval-shaped central portion i, with curved 45 openings j j therethrough, said openings having scroll-shaped upper ends; also, a transverse front piece L just below and in contact with the front of the seat F and extending between the front legs E E, there being no 50 lower cross-piece between said front legs.

Having thus described my invention, what I claim as new, and desire to secure by Letters Patent, is—

The design for a chair, substantially as 55 herein shown and described.

In testimony whereof I affix my signature in presence of two witnesses.

ARA D. CROCKER.
